(57) **CLAIM**

The ornamental design for a tic-tac-toe game as shown and described.

DESCRIPTION

FIG. 1 is a perspective view of a tic-tac-toe game illustrating a first side with game inputs in a first orientation.

FIG. 2 is a top view of the tic-tac-toe game.

FIG. 3 is a bottom view of the tic-tac-toe game illustrating a second side.

FIG. 4 is a right side view of the tic-tac-toe game.

FIG. 5 is a left side view of the tic-tac-toe game.

FIG. 6 is a front side view of the tic-tac-toe game.

FIG. 7 is a rear side view of the tic-tac-toe game.

FIG. 8 is a perspective view of a first side of the tic-tac-toe game with three of the game inputs in a second orientation; and,

FIG. 9 is a perspective view of a first side of the tic-tac-toe game with three of the game inputs in a third orientation. The broken lines showing the letter(s) 'X' and 'O' are included for the purpose of illustrating the portions of the "article" and forms no part of the claimed design. The dash-dot-dash lines indicate boundary lines and form no part of the claimed design.

1 Claim, 6 Drawing Sheets
